UNITED STATES PATENT OFFICE

WILLIAM C. MASTERS, OF CORAOPOLIS, PENNSYLVANIA

TRACK LUBRICATOR

Application filed March 7, 1929. Serial No. 345,064.

This invention is for a lubricator for applying grease or oil to the head of a rail.

Various attempts have been made to provide automatic means for applying grease or lubricant to the inner face of the head of a rail on the curve of a railroad track, but such devices as have heretofore been provided have not been highly successful. The most successful form has been one wherein the lubricant is spread against the face of a head of a rail by compressed air, but such devices are of a rather complicated nature, they require the presence of a source of air under pressure, and are not generally satisfactory for the reason that the consistency of the lubricant changes with changes of temperature, and the spray nozzles are likely to become congested.

According to the present invention, there is provided a simple mechanical mechanism operated by the passage of a car wheel along the rail for applying lubricant to the portion of the rail which it is desired to lubricate. The lubricant which is thus applied is wiped along the rail by the car wheels so as to provide for the effective lubrication of the rail for some distance beyond the lubricator.

The invention may be readily understood by reference to the accompanying drawings, in which

Figure 1 is a view, partly in section and partly in side elevation, of one form of lubricating device embodying my invention, showing it in position against the inner face of a rail;

Figure 2 is a top plan view of the device shown in Figure 1;

Figure 3 is a view similar to Figure 1 of a slightly modified construction;

Figure 4 is a top plan view of the device shown in Figure 3;

Figure 5 is a transverse vertical section in substantially the plane of line V—V of Figure 1; and

Figure 6 is a similar view in substantially the plane of line VI—VI of Figure 3.

In the drawings, A designates one rail of a railroad track. The head of the rail is designated *a* and the base of the rail is designated *b*, while the web is designated *c*. A

standard rail plate is provided at B, and C designates the usual cross-tie.

In the construction as shown in Figure 1, the lubricator comprises a base plate 2 having a rectangular reservoir 3 thereon, this reservoir having inner and outer side walls 4 and 5, respectively, and having end walls 6. The inner portion of the plate 2 is slightly inclined so as to fit against the base of the rail, while lugs 7 are provided on the inner face of the base. These lugs engage the top of the rail plate B and serve to support the reservoir in a substantially horizontal position.

Tiltably mounted within the reservoir 3 is a lever 8. In the construction shown in Figure 1, the lever is supported substantially midway between its ends, and is provided with enlarged portions 9 at each end thereof. In each of these enlarged portions 9 in that face which is toward the head of the rail is a socket or cavity 10.

Received in each of the cavities 10 is a brush 11, this brush preferably comprising an ordinary bristle brush having a wooden or suitable base adapted to be received in the cavity 10. Passing through the back of each of the sockets are one or more set screws 12 adapted to bear against the back of the brush and by means of which the brush can be adjusted as the bristles wear down.

In the construction shown in Figure 1, the lever, which may be tiltably supported in any suitable manner, is illustrated as having a transverse knife edge bearing 13 which is received in a transversely extending V-shaped groove 14 in a lug 15 in the bottom of the reservoir 3. On the top of the lever 8 is a finger 16 which is adapted to project into a longitudinally extending groove or slot 17 in a keeper plate 17' which is over the top of the receptacle. There is provided also a cover plate 18 which is removably secured to the top of the reservoir, and is provided with openings 19 through which the brush carriers at each end of the lever may pass.

In use, the lubricator, which has an overall length sufficient to span two ordinary cross-ties as usually laid, is bolted to the rail plate on two adjacent ties with the inner side

wall 4 toward the web of the rail, the device being secured in position in such a way that there is slight clearance at 20 between the top of the wall 4 and the underside of the head of the rail. The inner face of the wall 4 is preferably in vertical alignment with the inner face of the head of the rail.

The lever 8 is over-weighted at one end, as shown in the drawings, wherein the left hand end is shown as being the heavier so as to overbalance the other end. The left hand end therefore normally remains in the reservoir, while the right hand end normally projects through the opening 19.

After the device has been secured in place, grease, oil or other lubricant to be applied to the inner face of the head of the rail, is put in the reservoir or receptacle 3. When the wheel of a train rolls along the rail, the flange of the wheel hits the top of the brush holder which is projecting through the opening 19, rocking the lever 8 and raising the opposite end of the lever through the opening. This will be better understood by reference to Figure 1, wherein the car wheel is indicated at X. When the wheel X strikes the elevated right hand end of the lever 8, that end will be depressed and the left hand end will be forced up. As the left hand end rises, the brush 11 thereof will smear or swab grease against the inner face of the head of the rail. As the wheel passes beyond the lubricator, the right hand end will again arise, and it, having become saturated with grease, will swab lubricant against the head of the rail. This operation is repeated with the passage of a wheel along the rail.

The lubricant which is smeared or swabbed onto the side of the rail by the brushes is, of course, picked up by the wheels and spread along the rail whereby the rail will be effectively lubricated for a considerable distance beyond the lubricator. The number of lubricators which need to be applied to a given curve is therefore relatively small, one being sufficient for some curves, while a greater number spaced a considerable distance from each other may be used on long curves where the traffic is heavy and considerable lubrication required.

It is desirable that the space 20 between the top of the inner wall 4 and the underside of the head of the rail be maintained in order to permit of the weaving or springing up and down movement of the rail as the train passes thereover, the space 20 providing the necessary clearance. In order to avoid the unnecessary wasting of lubricant, means is provided on the outside of the wall 4 for resiliently bearing against the underside of the head of the rail for closing the space 20 against the escape of lubricant. This means comprises a non-metallic strip, preferably a composite strip comprising a strip of leather 21 and a strip of felt 22. This composite

strip is supported on a flat leaf spring 23, and is confined against lateral movement by keepers 24 which are welded or otherwise secured to the outside of the wall 4. The leaf spring 23 serves to hold the upper edge of the composite strip against the underside of the head of the rail, while the keepers 24 allow the composite strip to slide up and down with the spring of the rail.

It will be obvious that instead of using a double ended lever as shown in Figure 1, an effective lubricator may be provided in which there is a lever having but one brush at one end thereof and having a counterweight at the other end. In the construction shown in Figures 3, 4 and 6, such an arrangement is provided, but instead of their being a single lever, I have shown an arrangement wherein there are two levers in each reservoir.

In the construction shown in Figures 3, 4 and 6, the general arrangement is substantially the same as that heretofore described. The base member 25 is provided with a rectangular receptacle or reservoir 26. Centrally positioned in the reservoir 26 is a bracket 27 having upstanding lugs 28. Extending across between the lugs 28 is a pin 29 on which is pivotally supported a lever 30 having a brush receiving end 31 in which is a brush 32. On the opposite end of the lever 30 is a counterweight 33 for normally maintaining the brush in elevated position. Carried on the pin 29 is a second lever 30' which is similar to the lever 30 but which is reversed with respect thereto, this lever having a brush holder 31' and a brush 32'. The lever 30' has counterweights 33'.

As shown in Figure 3, these levers are adapted to be actuated by the passage of a car wheel over the rail. In Figure 3, the brush 32 has been forced down into the grease receptacle while the brush 32' is in the elevated position. Upon passage of the car wheel from over the brush receptacle 31, the lever 30 will be returned to its normal position.

In order to secure free independent movement of the two levers, a washer 34 is provided on the pin 29 between the two levers. The pin 29 is removably secured in the lugs 28 by means of a keeper 35 over the head of the pin.

The construction shown in Figure 1 is preferable when the traffic moves slowly, as on a track where most of the trains are heavy freight trains, or at a point where the trains move slowly. Fast trains operate the device too violently, so that the construction shown in Figure 3 is preferable where the trains are traveling at high speed, as each brush operates independently and consequently more slowly and with less force on the upward travel of the brush. It will not throw grease the way the structure shown

in Figure 1 will when actuated by the wheels of a fast train.

My invention provides a simple mechanism actuated by the passage of a train along the track for effectively applying grease to the inner side of the head of the rail. It will be noted that the brush receiving receptacles are rounded on the top so that the car wheel will encounter a rounded surface rather than a sharp corner. When the brush receptacle is pushed clear down into the lubricant, it is clear of the flange of the wheel. Ordinarily the wheel of a train will hit the brush holder with sufficient force to rock the lever all the way down so that there is always plenty of clearance between the flange of the wheel and any portion of the lubricator, and no portion of the lubricator can be crushed or broken by the passage of the car wheel along the track.

The car wheel in passing along the rail provides ample power for operating the lever so that the lubricator will work in any kind of weather. In the operation of the lubricator, the lever is rocked many times in the passage of a train thereover. This movement of the lever keeps the lubricant stirred up and loose. Not only does the lever serve to agitate the lubricant, but the lubricant tends to cushion the lever when it is forced down with considerable impact by the passage of a fast train thereover.

It will, of course, be understood that springs may be used in place of counterweights, and that various other departures and variations may be made in the construction and arrangement of parts, and that the particular constructions herein specifically shown and described are merely illustrative of certain embodiments of my invention, and the invention is not restricted to such embodiments.

I claim as my invention:

1. The combination with a rail, of a lubricant reservoir, a counterweighted lever having a wheel-engaging portion thereon, and a swab on the lever adapted to receive grease from the reservoir and wipe it against the face of the head of the rail.

2. In a track lubricator, a receptacle, a lever tiltably supported in the receptacle, said lever being supported between its ends, a lubricant applying element at each end of the lever, and a car wheel engaging portion at each end of the lever, one of said lubricant applying means being projected above the top of the receptacle when the other end of the lever is inside the receptacle.

3. In a track lubricator, a receptacle, a pair of rail lubricating swabs alternatively movable into and out of the receptacle and adapted to receive lubricant in the receptacle and apply it to the rails when they move out of the receptacle, said lubricant applying means having wheel engaging portions where-

by they are operated by the passage of a car wheel along the rail to which the lubricator is applied.

4. In a track lubricator, a receptacle adapted to be positioned along a rail with one edge thereof under the head of the rail and spaced below the head of the rail, a car wheel actuated swabbing device movable up and down from rail indicating position above the top of the receptacle to a lubricant receiving position within the receptacle, and means yieldably interposed between the receptacle and the underside of the head of the rail for retarding the escape of lubricant in the space between the top of the receptacle to the underside of the head of the rail.

5. In a track lubricator, a receptacle adapted to be positioned along a rail with one edge thereof under the head of the rail and spaced below the head of the rail, a car wheel actuated swabbing device movable up and down from rail indicating position above the top of the receptacle to a lubricant receiving position within the receptacle, means yieldably interposed between the receptacle and the underside of the head of the rail for retarding the escape of lubricant in the space between the top of the receptacle to the underside of the head of the rail, said means comprising a non-metallic strip movable vertically with respect to the receptacle, and means for resiliently supporting the strip.

6. A rail lubricator comprising a receptacle, a lever tiltably supported in the receptacle and having an end portion which is adapted to project above the top of the receptacle when the lever is tilted in one direction, and which is adapted to be received in the receptacle when the lever is tilted in the other direction, a wheel engaging portion on said end of the lever, and a lubricant applying element carried on said end of the lever and adapted to wipe across the inner face of the head of a rail when said lever is rocked from one position to the other and adapted to receive lubricant when said end of the lever is forced down into the receptacle.

7. A rail lubricator comprising a receptacle, a lever tiltably supported in the receptacle and having an end portion which is adapted to project above the top of the receptacle when the lever is tilted in one direction, and which is adapted to be received in the receptacle when the lever is tilted in the other direction, a wheel engaging portion on said end of the lever, and a lubricant applying element carried on said end of the lever and adapted to wipe across the inner face of the head of a rail when said lever is rocked from one position to the other and adapted to receive lubricant when said end of the lever is forced down into the receptacle, said lever being counterweighted whereby the end which has the wheel engaging portion thereon is normally in an

elevated position above the top of the receptacle.

8. A rail lubricator comprising a receptacle, a lever tiltably supported in the receptacle and having an end portion which is adapted to project above the top of the receptacle when the lever is tilted in one direction, and which is adapted to be received in the receptacle when the lever is tilted in the other direction, a wheel engaging portion on said end of the lever, and a lubricant applying element carried on said end of the lever and adapted to wipe across the inner face of the head of a rail when said lever is rocked from one position to the other and adapted to receive lubricant when said end of the lever is forced down into the receptacle, said lever being counterweighted whereby the end which has the wheel engaging portion thereon is normally in an elevated position above the top of the receptacle, said lubricant applying means being removably and adjustably carried in said end of the lever.
- 26 9. In a track lubricator, a receptacle, a counterweighted lever tiltably supported in the receptacle for vertical movement in a plane parallel with the plane of the rail to be lubricated, a wheel-engaging portion on the lever, the wheel-engaging portion being normally elevated to wheel-engaging position by the counterweighting of the lever, and a grease applying element on the lever adapted upon movement of the lever to receive the lubricant from the receptacle and apply it to the rail to be lubricated.

In testimony whereof I have hereunto set my hand.

WILLIAM C. MASTERS.
